UNITED STATES PATENT OFFICE.

FREDERICK MILTON WILLIS, OF NEW YORK, N. Y.

SHOE-LACE RETAINER.

982,332.

Specification of Letters Patent. Patented Jan. 24, 1911.

Application filed January 11, 1910. Serial No. 537,458.

To all whom it may concern:

Be it known that I, FREDERICK MILTON WILLIS, a citizen of the United States, and a resident of the city of New York, borough of Manhattan, in the county and State of New York, have invented a new and Improved Shoe-Lace Retainer, of which the following is a full, clear, and exact description.

This invention relates to certain improvements in devices adapted to be secured to or carried by shoes for receiving and retaining the ends of the shoe laces to prevent the latter from becoming accidentally untied.

In my improved construction, I provide a member which is secured to the body of the shoe adjacent the upper edge thereof, and is so constructed that it will receive and resiliently retain the bow of the knot in the shoe lace, and be partly concealed thereby and will independently receive the free end of the shoe lace.

The device is very simple in construction and may be very readily attached. When in use, it is inconspicuous and does not present any sharp edges or points which could possibly injure or tear the lower edge of a garment adjacent thereto.

One specific form of the device will be described hereinafter, together with many of the advantages of the same, and the scope of the invention will be defined in the claims.

Reference is to be had to the accompanying drawings, forming a part of this specification, in which similar characters of reference indicate corresponding parts in all the figures, and in which—

Figure 1 is a perspective view of a shoe provided with my improved lace fastening device; Fig. 2 is a section through a portion of the top of the shoe, showing the construction of the device; Fig. 3 is an elevation of a portion of the shoe with the device attached thereto.

My improved device is illustrated as including two pairs of separate elements independently secured to a shoe adjacent the upper edge thereof and upon opposite sides of the lacing. Of the two elements of each pair, one comprises an eyelet 10, while the other comprises a resilient catch or retainer 11. The eyelet does not differ materially from the common form of eyelets used in shoes, and through which the lacing is extended. Such eyelets are commonly in the form of rings extending through the wall

of the shoe and extending into engagement with the opposite surface of the latter. The retaining member 11 is preferably formed of metal and is secured to the wall of the shoe at a short distance below the eyelet 10.

The fastening means for the member 11 may be of any suitable kind, but preferably it is in the form of an eyelet 12, the body portion of the member being formed integral with the flange of the eyelet 12 and extending downwardly therefrom and thence upwardly to form a loop 13. The bent or loop portion is preferably flattened transversely of the member to form a resilient or spring connection, while the free end of the member is flattened in a plane substantially at right angles to the plane of the adjacent portion of the shoe. This outer or free end is provided with an aperture 14 therethrough, which is of sufficient size to receive the shoe lacing, and this free end is so disposed that it is normally pressed into the eyelet 10, as is indicated particularly in Fig. 2. The curved under edge of the free end of the member 11 fits down into the aperture of the eyelet, so that the latter constitutes a socket or receiver for said free end.

In attaching my improved fastener to the shoe, the eyelet 10 is placed closely adjacent the upper edge of the shoe and at a very short distance from the line of hooks or eyelets with which the lacing normally engages. The member 11 is supported below the eyelet, so that the member extends upward vertically. After the shoe is laced in the ordinary manner and the bow is formed, the entire bow may be slipped beneath the member 11, so as to rest in the bend or loop 13 thereof and be prevented from freely swinging or becoming untied. If desired, and in fact, preferably, only the inner portion of the loop is slipped beneath the member 11, so that the outer portion of the loop will lie outside of the member 11 and partially conceal the latter. I have not so illustrated the loop in Fig. 1, as it is desired to illustrate the construction as clearly as possible. After the loop is secured in position, the free or tying end of the lacing is inserted through the aperture 14; thus the loop and the tying end are independently secured in position and the tying end serves to prevent the loop from becoming displaced from its position in the rear of the member 11.

Having thus described my invention, I

claim as new and desire to secure by Letters Patent:

1. A shoe lacing retainer, comprising two members, one of said members comprising an eyelet, and the other of said members having an eyelet and a body portion connected thereto, said body portion being flattened adjacent its eyelet, to resiliently support the free end of said body, said free end having an opening therethrough in a direction parallel to the adjacent surface of the shoe, and said free end being normally pressed into the first-mentioned eyelet.
2. A shoe lace retainer, comprising a spring metal member extending substantially vertically below the upper edge of the shoe and spaced from and independent of

the lacing receivers of the shoe, said member at its lower portion constituting a transverse loop to receive the bow of the shoe lace, and having its upper end pressed resiliently toward the shoe wall but movable in respect thereto, to permit the entry of the lace into said loop, said upper portion having a transverse passage therethrough to receive the end of the shoe lace.

In testimony whereof I have signed my name to this specification in the presence of two subscribing witnesses.

FREDERICK MILTON WILLIS.
